FUR SEWING MACHINE

Caesar Bonis, Brooklyn, N. Y.

Application January 14, 1938, Serial No. 184,925

1 Claim. (Cl. 112—18)

This invention relates to fur sewing machines and more particularly to the driving mechanism of the material feeding disks thereof, said driving mechanism being of the intermittent type. 5 One object of the invention is the provision of a driving mechanism of this nature which is both positive and instantaneous on the forward and return stroke thereof.

Another object of the invention is the provision of a device of the character referred to which will include means for positively braking the material feeding disks against rotation when the needle is in the forward or needle plate position. 10

15 A further object of the invention is the provision of a retainer for positively holding the drive shaft of the device against rotation on the idle or return stroke of the clutching member forming a part of the driving mechanism.

20 Another object is to produce a device of the character described in which the maximum simplicity of construction and operation is secured.

Other objects and advantages will appear as the nature of the improvements is better understood, the invention consisting substantially in the novel arrangement and co-relation of parts herein fully described and illustrated in the accompanying drawings, wherein similar reference characters are used to describe corresponding 25 parts throughout the several views, and then finally pointed out and specifically defined and indicated in the appended claim.

The disclosure made the basis of exemplifying the present inventive concept suggests a practical embodiment thereof, but the invention is not to be restricted to the exact details of this disclosure, and the latter, therefore, is to be understood from an illustrative, rather than a restrictive standpoint.

40 In the accompanying drawings;

Figure 1 is a side view in elevation of a fur sewing machine with sufficient of its mechanism shown to aid in the explanation of the present invention;

45 Figure 2 is a front view thereof;

Figure 3 is a fragmental sectional view taken on line 3—3 Figure 2;

Figure 4 is a longitudinal sectional view taken on line 4—4 Figure 1 with the worm gear represented diagrammatically;

Figure 5 is a sectional view taken on line 5—5 Figure 4;

Figure 6 is a sectional view taken on line 6—6 Figure 4, and

55 Figure 7 is a longitudinal sectional view with

the parts in somewhat different position than shown in Figure 4 of a modified form of the invention.

Referring now to Figures 1 to 6 of the drawings in detail 10 indicates the main drive shaft 5 of the machine upon which the usual driving pulley 11 is mounted. Secured to the shaft 10 is an eccentric or cam 12 encircling which there is a hub 13 of a lever 14 the lower end of which is secured to the rear end of a horizontally disposed rocker arm 15 mounted upon a pivot 16 slidably adjustable in a slot 17 in one wall of the machine frame 18. The rocker arm 15 is provided with an elongated slot 19 to permit of adjustment of the pivot 16. 15

The driving mechanism for the material feeding device comprises a horizontal drive shaft 20 mounted upon trunnions 21 and 22 and has secured to one end thereof a drum 23 having a cylindrical recess or chamber 24 concentric with the said shaft and in which is located a clutch member 25 loosely mounted upon the shaft 20. The said member 25 is provided with four undercuts or recesses 26 each of which is provided with a peripheral curved and eccentric surface 27. Projecting arms or extensions 28 are formed between the undercuts 26 and the said extensions are each provided with an aperture or hole 30 in which there is mounted a coiled spring 31 exerting a tension against a headed stud or 30 plunger 32 in contact with a roller 33 to force the said roller toward the narrow end of its undercut 26 and wedge same between the eccentric surface 27 and the peripheral surface of the recess or chamber 24. 35

Secured to the member 25 by means of screws 35 is an end plate 36 which is provided with a pair of ears 37 which carry screws 38, the heads of which are in engagement with one surface of an annular flange 39 on the drum 23 40 to connect the end plate 36 to the drum and to prevent the clutching member 25 and rollers 33 from falling out of the chamber 24. The end plate 36 is further provided with an ear or extension 40 (see Figures 1 and 2) to which 45 is secured by means of a stud 41 the forward end 42 of the rocker arm 15.

The end of the drum 23 opposite to the flange 39 is provided with a recess or depression 44 forming an annular ring 45 which is serrated 50 to form a worm gear having teeth 46 adapted to mesh with the curved worm-like teeth 47 of a gear 48 secured to the lower end of a vertical shaft 49 to the upper end of which is secured one material feeding disk 50. The shaft 49 is 55

rotatably mounted in frame 18 and in a boss 51 at the front of the said frame. Collars 52 and 53 secured to the shaft 49 one above and the other below the boss 51 prevent vertical movement of the said shaft. A second material feeding disk 54 in operative engagement with the disk 50 is carried upon an arm 55 suitably supported on the frame 18 at 56 and 57. The disk 54 is provided with the usual needle plate 58 to receive the needle 59 when in forward position the said needle being carried by the needle rod 60 and operated by means forming no part of this invention.

Secured to the shaft 20 at the end opposite to which the drum 23 is secured, is a shaft retainer or reverse rotation restraining means comprising a housing 61 provided with a recess or chamber 62 concentric with the shaft 20 (see Figures 2, 3 and 4). Located within the said recess 62 is a clutch member 63 similar in all respects to the clutch member 25 but is provided with three undercuts or recesses 64 each of which is provided with a peripheral curved and eccentric surface 65. Arms or extensions 66 formed between the undercuts 64 are each provided with a hole or aperture 67 for the reception of a headed plunger 68 which is pressed forwardly against a roller 69 by means of a spring 70 to force the said roller toward the narrow end of the undercut 64 and wedge same between the curved surface 65 and the periphery of the chamber 62. Secured to the clutch member 63 by means of screws 71 is a cover-plate 72 having an extension or arm 73 (see Figure 3), which is fastened to the frame 18 of the machine by means of a screw 74. The plate is maintained in position on the housing 61 by means of a headed screw 75 in engagement with a flange 76 on the said housing and by a plate 77 secured to the plate 72 and in engagement with the flange 76.

The operation of the device is as follows:

Rocking movement to the rocker arm 15 is imparted by the eccentric operated lever 14. When the rear end of the said rocker arm 15 is swung downwardly the forward end of the said rocker arm will rotate the drum 23 and gear 45 in clockwise direction through the connections 36, 41 and the clutching member 25 and rollers 33, said movement being transferred to the shaft 20 and therethrough to the housing 61. During the said rotary movement the gear 45 will drive the material feeding disks 50 and 54 through the gear 48 and shaft 49. When the lever 14 pulls the rear of rocker arm upwardly the clutch member 25 will be carried or swung out of wedging engagement with the rollers 33 and will idle back without rotating the shaft 20 or drum 23 until the rear of the rocker arm is again swung downwardly. I find that due to the curved eccentric surfaces 27 the clutching and disengaging action is instantaneous.

The clutch mechanism contained within the housing 61 acts as a brake for the shaft 20 which is held against backward movement or rotation during the idling movement of the driving clutch member 25. The said braking or retaining action is accomplished by means of the plate 72 which is secured to the machine frame and held stationary by the screw 74. It will be remembered that the clutch member 63 is secured to the said plate 72 and cannot therefore move out of wedging engagement with the rollers 69, thus assuring and providing positive retaining means for the said shaft 20.

Due to the curvature of the gear-teeth 46 and

47 practically all of the back lash between the said gears is eliminated thus providing a braking or locking action between the gears 45 and 48 against manually rotating the material feeding disks. This braking action is very desirable or essential, since no movement of the disks 50 and 54 is permissible during the period when the needle 59 in engagement with the needle plate 58, since such movement would cause the needle to break. The period when the needle is in engagement with the needle plate 58 corresponds or coincides with the period during which the driving clutch 25 is idling.

In Figure 7, I have shown a modified form of my invention wherein, instead of using a combined drum and gear in the driving clutch mechanism, I employ a gear 45^a having the gear teeth 46 in the end edge thereof, the said gear being secured to the shaft 20 by means of one or more set screws 75. Secured to the rear wall of said gear 45^a by means of pins or rivets 76 is a clutch member 25^a which is in all respects similar to the clutch member 25 and is provided with the cooperating rollers 33 and springs and plungers 31 and 32 respectively, the said rollers, springs and plungers not being shown as the section is so taken where they cannot be seen. A separate loose fitting ring 77 encircles the clutch member the inner surface or circumference 18 thereof acting in the same capacity as the surface 24 of the drum 23. Secured to the ring 77 is a cover plate 36^a which is connected to the forward end of the rocker arm 15.

The retaining means in this form of the invention comprises a sleeve 80 secured to the shaft 20, and to which sleeve there is secured in any desirable manner the clutching member 63. A ring or housing 61^a is loosely mounted on the sleeve 80 and has secured thereto the plate 72 the arm 73 of which is secured to the frame of the machine as in the first form of my invention. In the interior of the ring 61^a there are located the rollers 69 and the member 63 carries the spring pressed plungers 68 as shown in Figure 5. The ring 61^a and the plate 72 are maintained on the sleeve 80 by means of a washer 81 and a headed over portion 82 at the end of the sleeve 80. The plate 72 may be secured to the ring 61^a by pins or rivets 83 or by any other suitable means.

The modified form of the invention herein shown like the form shown in Figures 1 to 6 is oscillated by the rocker arm 15, but instead of moving the drum 23 and housing 61 about the respective clutching members 25 and 63, the said clutching members are moved within the respective interiors of the ring 77 and housing 61^a, the net final results being the same as in the form of my invention first described.

From the foregoing it will be seen that I have provided a simple and efficient intermittent driving mechanism for the material feeding disks of fur sewing machines, one which will positively and instantaneously clutch on the operating or material feeding end of the movement and which will just as readily and positively release on the idling or return end of the movement.

It will further be seen that my device also provides efficient braking and shaft retaining means which will not permit of reverse movement of the drive shaft on the return end of the driving clutch mechanism and will likewise prevent any rotation of the material feeding disks when the needle has penetrated the material sewn and is in the needle plate.

Having described my invention, what I claim

as new and desire to secure by Letters Patent is:

An intermittent driving mechanism for a sewing machine comprising a shaft, a drum secured to the shaft and having a recess at one end concentric with the shaft and having a peripheral surface, a gear at the other end of said drum, a clutch member loosely mounted on the shaft within the recess of said drum and having peripheral recesses with eccentric and curved inner wedging surfaces confronting the peripheral surface of the drum, rollers in the recesses of said clutch member, spring pressed plungers carried by said clutch member in engagement with said rollers to force the same into clutching engagement with the wedging surfaces of the clutch member and the peripheral surface of the drum recess, a plate secured to the clutch member, means for oscillating said plate, a shaft retainer on said shaft

in spaced relation to the clutching means, said retainer comprising a cup-shaped housing secured to the shaft and having an inner peripheral surface, a clutch member loosely mounted on the shaft and having peripheral recesses with curved and eccentric surfaces confronting the peripheral surface of the housing, rollers in said recesses, spring pressed plungers carried by the clutch member to force its rollers into wedging engagement with the interior peripheral surface of the housing and the curved and eccentric clutch surfaces, a plate secured to the clutch member, a second shaft disposed transversely of the first mentioned shaft intermediate the drum and the shaft retainer, and a gear on the second mentioned shaft in mesh with the first mentioned gear.

CAESAR BONIS.
